CLAIM

The ornamental design for an electronic circuit board
rework and repair system, as shown and described.

DESCRIPTION

FIG. 1 is a perspective view of an electronic circuit
board rework and repair system showing our new de-
sign;

FIG. 2 is a front elevational view thereof on a reduced
scale;

FIG. 3 is a top plan view thereof on a reduced scale;
FIG. 4 is a back elevational view thereof on a reduced
scale;

FIG. 5 is a right end elevational view thereof on a re-
duced scale; and

FIG. 6 is a left end elevational view thereof on a re-
duced scale.

FIG. 1

FIG. 2

FIG. 3
